ALBERT H. TRAGESER AND LOUIS HASSINGER, OF NEW YORK, N. Y.

STEEL JACKETED COPPER BOILER

Application filed October 20, 1928. Serial No. 313,770.

This invention relates to reinforced copper boilers, and particularly to an improved steel jacket for covering and reinforcing a copper boiler, the object being to provide a completely and correctly formed copper boiler and then cover the same with a snug fitting steel jacket, whereby a minimum amount of copper may be used and yet a maximum pressure resisting structure secured.

- 10 Another object of the invention is to provide a steel jacketed copper boiler, wherein the jacket is formed in several parts and welded together after having been fitted over the copper boiler.
- 15 A further object of the invention is to provide a copper boiler with a covering of asbestos or other heat insulating means and then reinforcing the boiler by a complete jacket of steel welded or otherwise rigidly secured together and in position over the boiler.

In the accompanying drawings,—

- Figure 1 is a side view of a copper boiler with certain parts broken away;
- 25 Figure 2 is a side view of the boiler shown in Figure 1, but with the jacket embodying the invention applied thereto, certain parts being shown in section for illustrating the arrangement of the boiler, jacket and heat insulating members;

Figure 3 is a perspective view showing the two end jacket members disclosed in Figure 2;

Figure 4 is a perspective view of the central jacket member shown in Figure 2.

Referring to the accompanying drawings by numerals, 1 indicates a copper boiler, and 2 indicates broadly a steel jacket adapted to completely enclose the boiler 1, except the outlet members. Between the steel jacket 2 and boiler 1 is a lining 3 of asbestos or other heat insulating material.

In the use of large copper boilers for supplying hot water or for other purposes, a large amount of copper is necessary in order to make the boilers sufficiently strong to withstand the pressure created by heating the water. To overcome the disadvantage of using a large supply of copper for a given size of boiler, the steel jacket 2 is used to enclose

a boiler of copper made of comparatively thin copper. Where there is no jacket the boiler 1 must be made very thick, but where there is a steel jacket this boiler may be made very thin and be properly supported by the jacket 2. As clearly shown in Figure 1, the boiler 1 is formed in the usual manner of copper boilers with the end members 12 having their depending flanges 12' telescoping interiorly of the body 4, so that they may be welded in place in the usual manner of welded boilers. The various outlets may be also secured in place in any usual preferred manner. On top of the boiler 1 is applied part of the lining or covering 3 of asbestos or other heat resisting material and then the end jacket members 5 and 6 are placed in position. These jacket members are of steel and are made of an exact size and shape to snugly fit over the lining 3. Suitable openings are provided for accommodating certain of the outlets. Arranged centrally of the boiler is a jacket band 7 of steel. This band is shown open in Figure 4 and in this condition is mounted in place. After being mounted in place the band is squeezed tightly against the lining 3 and against portions of the end members 5 and 6 which are overlapped thereby. The parts are so proportioned that when the jacket band 7 is properly squeezed into place, as shown in Figure 2, the edges 8 and 9 may be welded together. This band is also welded along the top and bottom lines 10 and 11 to the end members 5 and 6, whereby the steel jacket is substantially one-piece. It will thus be seen that a complete working boiler is provided, as shown in Figure 1, and on top of this is applied a complete and practically one-piece steel jacket with a heat insulating lining 3 arranged exteriorly of the boiler and interiorly of the jacket. By providing the steel jacket, a very thin sheet of copper may be used in forming the boiler 1, but by forming the boiler and jacket independently an extra-efficient structure is produced in the capacity of the boiler to be water and steam tight and to resist high pressure through the action of the jacket.

What I claim is:—

1. A steel jacketed copper boiler, com-

prising a copper boiler and a steel jacket therefor, said steel jacket being formed of a plurality of pieces welded together and the boiler being formed of a plurality of copper pieces welded together, the line of welding of the copper boiler being out of alignment with the line of welding of the steel jacket, the walls of said steel jacket being uninterrupted whereby the jacket will provide an even support over the entire surface of said copper boiler including the ends thereof.

2. A steel reinforced copper boiler comprising a boiler formed of copper having an outlet and a steel reinforcing jacket for said boiler, said jacket consisting of a cup shaped member at each end of the boiler and a central tubular member at the center of the boiler, said members fitting over and completely enclosing the copper boiler, said tubular member overlapping the cup shaped members, all of said members being continuous and uninterrupted whereby an even support is provided over the entire surface of said boiler including the ends thereof.

25 3. A steel reinforced copper boiler comprising a boiler formed of copper and provided with a number of outlets, a steel reinforcing jacket for said boiler formed of a pair of cup shaped members and a tubular member, said tubular member being arranged centrally of the copper boiler and overlapping the end members, said jacket completely enclosing said copper boiler, a heat-insulating lining arranged between said boiler and said jacket, said lining covering said boiler including the end and acting to resist radiation of heat from the boiler, and also as a means for transmitting pressure from the boiler to the jacket.

40 4. A steel reinforced copper boiler comprising a boiler body formed of copper provided with a number of outlets, a built-up steel reinforcing jacket surrounding said body and acting in effect as a continuous one-piece tubular structure covering the entire copper boiler including the ends, and a heat insulating filling positioned between said body and said jacket for resisting the passage of heat from said body and for transmitting strain from said body to said jacket.

LOUIS HASSINGER.
